(57) **CLAIM**

We claim the ornamental design for an electronic device, as shown and described.

DESCRIPTION

FIG. 1 is a front perspective view of an electronic device showing our new design;
FIG. 2 is a front elevational view thereof;
FIG. 3 is a rear elevational view thereof;
FIG. 4 is a left-side elevational view thereof;
FIG. 5 is a right-side elevational view thereof;
FIG. 6 is a top plan view thereof;
FIG. 7 is a bottom plan view thereof;
FIG. 8 is another perspective view thereof showing the electronic device in a first partially open position;
FIG. 9 is a front elevational view thereof;
FIG. 10 is a rear elevational view thereof;
FIG. 11 is a left-side elevational view thereof;
FIG. 12 is a right-side elevational view thereof;
FIG. 13 is a top plan view thereof;
FIG. 14 is a bottom plan view thereof;
FIG. 15 is another perspective view thereof showing the electronic device in a second partially open position;
FIG. 16 is a front elevational view thereof;
FIG. 17 is a rear elevational view thereof;
FIG. 18 is a left-side elevational view thereof;
FIG. 19 is a right-side elevational view thereof;
FIG. 20 is a top plan view thereof;
FIG. 21 is a bottom plan view thereof;

(Continued)

FIG. 22 is another perspective view thereof showing the electronic device in a third partially open position; FIG. 23 is a front elevational view thereof; FIG. 24 is a rear elevational view thereof; FIG. 25 is a left-side elevational view thereof; FIG. 26 is a right-side elevational view thereof; FIG. 27 is a top plan view thereof; FIG. 28 is a bottom plan view thereof; FIG. 29 is another perspective view thereof showing the electronic device in an open position; FIG. 30 is a front elevational view thereof; FIG. 31 is a rear elevational view thereof; FIG. 32 is a left-side elevational view thereof; FIG. 33 is a right-side elevational view thereof; FIG. 34 is a top plan view thereof; FIG. 35 is a bottom plan view thereof; and, FIG. 36 is an enlarged view of the encircled portion in FIG. 6. The evenly dashed broken lines in the figures show portions of the electronic device which form no part of the claimed design. The dot-dashed broken lines encircling portions of the claimed design that are illustrated in enlargements form no part of the claimed design.
